(57) **CLAIM**

The ornamental design for a side handle for cooking utensil, as shown and described.

DESCRIPTION

FIG. 1 is a side elevational view of a side handle for cooking utensil, showing my new design, the view of the side opposite that shown in FIG. 1 being the mirror image thereof;

FIG. 2 is a top plan view thereof;

FIG. 3 is a bottom plan view thereof;

FIG. 4 is an end view thereof;

FIG. 5 is a view thereof from the end opposite that shown in FIG. 4; and,

FIG. 6 is a top and side perspective view thereof.
